UNITED STATES PATENT OFFICE.

JACOB BUCHLI, OF WINTERTHUR, SWITZERLAND.

OIL-MOTOR-DRIVEN LOCOMOTIVE.

Application filed August 27, 1926, Serial No. 131,952, and in Germany October 26, 1925.

The present invention relates to improvements in oil-motor driven locomotives and particularly to the arrangement of the cylinders of the internal combustion engine in 5 Diesel locomotives of large output.

The arrangement of oil motors of large output on locomotives presents considerable difficulties which are overcome by the present invention. Up to the present the following types of motors have been utilized on locomotives: Vertical motors with cylinders arranged in one line, motors with cylinders arranged in V-fashion or horizontal motors with their crank shaft parallel or transverse 10 to the axis of the locomotive and their cylinders staggered in the known manner. All these arrangements present the important disadvantage that it is impossible to install motors of large outputs as the space required 15 and the weight of motors built in this manner are excessive.

The novel arrangement makes it possible to utilize the whole cross-sectional area of the vehicle in the horizontal direction and to 20 reduce the weight of the motors per horse power installed to a minimum.

The oil-motor or internal combustion engine according to the present invention comprises a plurality of preferably horizontally arranged cylinders disposed in two rows 25 and each cylinder of one row being opposite a cylinder of the other row with their axes in the same plane extending at right angles to the longitudinal centre plane of the locomotive or with their axes in alignment when the cylinders are horizontally disposed, the cylinders working on a crankshaft common to all the cylinders and arranged in the longitudinal centre plane of the locomotive.

An important advantage of this arrangement 30 consists in the fact that the valves and the valve gear are situated at the outer side so that they are easily accessible and removable. The valve gear may be so arranged and enclosed that its noise does not annoy the attendants on the locomotive nor other people. Further this horizontal arrangement of the cylinders permits a good utilization of the available space and the provision of only one driver's cab as the driver has an unobstructed view over the group of cylinders. Thereby a further saving in weight results. The provision of two lateral gangways above the engine on the locomotive is possible as no apparatus has to be placed there. The crank shaft may be

easily removed and all the bearings are readily accessible from above.

As the number of pairs of opposed cylinders, which form the elements of which the engine is composed, may be chosen according to the desired output a very wide range of power may be provided by joining a greater or smaller number of such elements to each other.

Constructional examples of the subject matter of the present invention are diagrammatically illustrated on the accompanying drawings, in which:

Fig. 1 shows in elevation the arrangement of the cylinders of the oil motor on a locomotive.

Fig. 2 shows this arrangement in a plan view and

Fig. 3 in a cross-section of the locomotive.

Fig. 4 shows the same arrangement of the cylinders of the oil motor as in Fig. 1; however different means for transmitting the output of the motor to the driving axles are diagrammatically indicated, and

Figs. 5 and 6 show the connecting rods of the pair of opposed cylinders.

The oil motor 1 is composed of a number of pairs of cylinders 2, 2', 3, 3' and so on, the cylinders of each pair being arranged opposite each other with their axes in alignment and all the cylinder pistons work on one common crank shaft 10 extending in the longitudinal direction of the locomotive. The latter is connected by means of the coupling 11 to the gear 12 and the drive of the axles 13 of the locomotive is effected by means of the shaft 14 and gear wheels arranged in the casings 15.

The cylinders 2, 2', 3, 3' and so on are arranged in pairs and each pair forms an element. The oil motor can be readily built of any output by joining any desired number of such elements one beside the other.

Fig. 4 shows a locomotive in which the cylinders of the oil motor are arranged in the same manner as in Fig. 1, i. e. in pairs 2, 2', 3, 3'. Instead of the transmission gears interposed between the engine crank shaft and the driving axles electric transmission is installed. The oil motor is directly coupled with an electric generator 16 and the current generated is used in electric motors 17 which drive on the driving axles by means of the gear wheels 18, 19.

In Figs. 5 and 6 the two connecting rods or pitmen of a pair of opposed cylinders are

illustrated in a side view and in a plan view with parts shown in section respectively. Each two cylinders of the pair work on the same crank of the crank shaft and the two connecting rods 20 and 21 have a connecting rod head which is common to both rods. Each connecting rod is provided at its one end with a closed head 22 adapted to cooperate with the piston pin and at its other end 10 with a bearing segment 23 cooperating with the crank pin and provided with an anti-friction lining 24. The two bearing segments 23 are embraced by two bi-partite coupling members 25 provided with an anti-friction lining 26 against which the outer faces of the segments 23 bear. The two parts of the coupling members 25 are held together by bolts 27.

The feature that each pair of opposed cylinders drives on the same crank shaft permits a very considerable reduction in the space required by the engine in the longitudinal direction so that a large number of cylinders can be placed in the available 25 space.

I claim:

1. An internal combustion engine for Diesel-locomotives of large output having a plurality of cylinders arranged on both sides 30 of the longitudinal centre plane of the locomotive, each pair of cylinders arranged opposite each other having their axes in the

same plane extending at right angles to the longitudinal axis of the locomotive, a crank-shaft extending in the longitudinal direction of the locomotive and having a plurality of crank pins, and connecting rods for transmitting the power from every cylinder to said crank pins, said connecting rods having at their outer ends segment shaped bearing bushes, and coupling members embracing the bearing segments of the connecting rods of every two opposed cylinders which cooperate with the same crank pin.

2. An internal combustion engine for Diesel-locomotives of large output, comprising a plurality of elements arranged beside each other and rigidly connected to each other, each element consisting of two cylinders arranged opposite each other with their axes in alignment, connecting rods for transmitting the power from each cylinder, said connecting rods having at their outer ends segment-shaped bearing bushes and coupling members embracing the bearing segments of the connecting rods of each element, and a crank shaft extending in the longitudinal direction of the locomotive between the cylinders of each pair and having a number of crank pins which corresponds to the number of said elements.

In testimony whereof, I have signed my name to this specification.

JACOB BUCHLI.
